UNITED STATES PATENT OFFICE

2,042,535

METAL TANK VAPOR ELECTRIC DEVICE

Oskar Krines, Berlin, Germany, assignor to General Electric Company, a corporation of New York

Application August 7, 1931, Serial No. 555,828
In Germany August 15, 1930

6 Claims. (Cl. 250—27.5)

My invention relates to metal tank vapor electric devices such as the mercury arc rectifier for the transfer of power between alternating and direct current circuits, particularly to means for insulating the anodes and anode leads of such devices from the metal tank and for mounting the anode shields, and its object is the provision of an improved arrangement of this character.

In a well known arrangement for conducting current to the anode of a metal tank rectifier from outside of the evacuated space within the container, a tubular member of metal or of insulating material is mounted on the upper wall of the tank, this member supporting an anode lead or current conducting member sealed vacuum tight by means of rubber, asbestos, mercury or the like, the sealing materials being mounted at a distance from the upper surface of the container which is determined by the heat conductivity and temperature control conditions in a given installation. This arrangement has the disadvantages that comparatively long anode lead-in insulators are required and that glow discharges may occur at the insulators.

In accordance with my invention these difficulties are avoided by the provision of an arrangement for conducting current to the anode whereby the anode current conducting and the anode sealing means, preferably including the well known heat resisting lead borate and mica insulating composition, are mounted within the evacuated container proper, substantially all of those surfaces of the anode structure and parts associated therewith which do not receive the arc discharge being located in a space which is at atmospheric pressure instead of vacuum. For this purpose the anode is mounted, by means of a molded insulating member, on a tubular supporting member connected at one extremity to the upper wall of the evacuated container and extending downwardly into the space within the container. The anode current conducting means comprises a rod mounted centrally of the tubular member and connected to the anode structure. The insulating supporting means for the anode shield surrounds the insulator which is mounted between the anode and the tubular member, and protects this intermediate insulating and sealing member from damage or destruction by the arc or by glow discharge.

My invention will be better understood from the following description when considered in connection with the accompanying drawing and its scope will be pointed out in the appended claims.

Referring to the drawing, the single figure thereof is a fragmentary sectional view of a vapor electric device embodying my invention.

In the figure, 1 represents the upper wall of a vapor electric device such as a mercury arc rectifier or inverter. In assembling the structure,

comprising the anode and related parts, which is to be connected to the wall 1 a tubular metal member 2 is first connected to a tubular internally flanged member 3 by means of a tubular insulating and sealing member 4 which is preferably formed of a lead-borate mica composition molded to the members 2 and 3, the connected parts 2, 3, and 4 being then finished. An externally threaded metal member 5 and a tubular connecting member 6 are then welded to opposite ends of the structure formed by the parts 2, 3, and 4, parts 3 and 5 together forming an anode supporting member and parts 2 and 6 forming a tubular metal supporting member for the anode, anode seal and other related parts. The entire assembly above described is connected to the wall 1 by welding tube 6 to the wall at a suitable opening formed therein.

A protecting insulator 7 having a cylindrical opening therethrough and forming a support for an anode shield or housing 8 is next slid over the lower end of the tubular element formed by the connected members 5, 3, 4, 2, and 6. This protecting insulator surrounds the anode insulator 4, the upper end of the anode supporting member formed by members 3 and 5, and the lower end of the tubular supporting member formed by members 2 and 6, and is maintained concentrically of members 3, 4, and 2 by ribs 9 between which are formed spaces or channels 10. A cup shaped anode 11 threaded internally is then screwed to the externally threaded member 5, the protecting insulator 7 being supported by the rim portion of the anode 11 and held in position between this rim and an external flange 12 formed on metal member 2, the joint between the anode 11 and the protecting insulator 7 being made gas tight by means of a quartz ring 13 having ground surfaces and interposed between the anode rim and the lower edge of the insulator 7.

In order to insure a good thermal contact between the anode and the anode supporting member, a layer 14 of a granular contact substance such as iron, graphite or the like is provided between these members. Channels 15 formed in externally threaded member 5 are provided to conduct to the tank space any gas or vapor which may be given off in the region of the layer 14. This gas or vapor flows from channels 15 into the annular channel 10, which is continued below the lower edge of protecting insulator 7 and between the inner members 3 and 5 and the quartz ring 13 and upper portion of anode 11, and thence out through the narrow openings 16. Since the quartz ring 13 by reason of its ground surfaces prevents gas flow into the anode space 17, all disturbing gases and vapors from the above mentioned source remain outside of this anode space.

To supply potentials to the anode 11 a con-

60

ducting member or rod 18 extending outside of the rectifier is mounted centrally of the tubular element formed by members 5, 3, 4, 2, and 6 and is screwed into the externally threaded member 5 at the central point 19 thereof.

In order to control the temperature of the anode insulating and sealing means 4 the tubular element formed by members 5, 3, 4, 2, and 6 is filled with an insulating liquid 20 such as oil or tetrachloride and this liquid is maintained at a predetermined temperature by means of a coil 21 which extends into the space formed by this tubular element and through which a heating or cooling medium may be circulated. A cover 22 of insulating material prevents the entrance of impurities into the space within the tubular element.

It will be seen that the space in the interior of the tubular element formed by members 5, 3, 4, 2, and 6 is at substantially atmospheric pressure, since the insulating member 4 forms a gas tight seal between this space and the highly evacuated anode space 17, and since the tubular element is open to atmospheric pressure at its upper end, the member 22 merely serving as a cover for this tubular element.

By suitably selecting the temperature of the insulating liquid 20 the temperature at the surface of the insulating and sealing member 4 is so adjusted that no condensed mercury will collect on this insulator. Therefore, the insulator may be surrounded by a protecting insulator or a metal tube placed at such a short distance therefrom that all discharge phenomena between these members are prevented, without at the same time the occurrence of short circuits in the narrow space between the members due to condensation of mercury vapor.

What I claim as new and desire to secure by Letters Patent of the United States, is:

1. In a vapor electric device, an evacuated metal container, an anode, an anode shield, an anode insulator connected in vacuum tight relation to said anode, an anode lead connected to said anode, means including a metallic member connected in vacuum tight relation at opposite ends thereof to said metal container and to said insulator to mount said insulator and said anode lead entirely within said container, said insulator constituting the sole insulating sealing means between said container and said anode, and an insulating member surrounding said anode insulator and connected to said anode shield.

2. In a vapor electric device, an evacuated metal container, an anode, an anode insulator connected in vacuum tight relation to said anode, an anode lead connected to said anode, means including a metallic member connected in vacuum tight relation at opposite ends thereof to said metal container and to said insulator to mount said insulator and said anode lead entirely within said container, said insulator constituting the sole insulating sealing means between said container and said anode, a protecting insulator connected to said anode shield, and means associated with said metallic member and said anode to mount said protective insulator so as to surround said anode insulator.

3. In a vapor electric device, an evacuated metal container, a cup shaped anode, an anode shield, an anode insulator, an anode lead, an anode mounting member connected to said anode lead and connected in vacuum tight relation to said anode insulator, a metallic member enclosing said anode lead, one end of said metallic

member being connected to said metal container and the other end thereof being connected in vacuum tight relation to said anode insulator to mount said insulator and said lead entirely within said container, said insulator constituting the sole insulating sealing means between said container and said anode, and a protecting insulator surrounding said anode insulator and connected to said anode shield, said cup shaped anode being detachably connected to said anode mounting member, the rim of said anode forming a support for said protecting insulator.

4. In a vapor electric device including an evacuated metal container and an anode mounted therein connected to means for conducting current from without said container to said anode, said device including an anode insulator adapted to be mounted vacuum tight between said container and said anode, means to mount said current conducting means and said anode insulator entirely within said container including a tubular metal member extending within said container and enclosing said current conducting means, said tubular member being connected at one end thereof to said container and at the other end to said anode insulator, said insulator constituting the sole insulating sealing means between said container and said anode, and means including an insulator mounted between said anode and said tubular member and surrounding said anode insulator to protect said anode insulator from the arc and glow discharges within said device.

5. In a vapor electric device, an evacuated metal container, an anode mounted therein, an anode lead and an anode insulator connected to said anode, a tubular metal member extending within said container and enclosing said anode lead, said tubular member being connected at one end thereof to said container and at the other end to said insulator, said insulator constituting the sole insulating sealing means between said container and said anode, and means including an insulating fluid within said tubular member and in contact with said insulator to maintain the outer surface of said insulator at a temperature at which mercury does not condense thereon.

6. In a vapor electric device, an evacuated metal container, an anode mounted therein, an anode shield, an anode insulator, an anode lead, an anode mounting member connected to said anode insulator and to said anode lead, a metal member extending within said container and connected at its opposite ends respectively to said container and to said anode insulator, said anode insulator constituting the sole insulating sealing means between said container and said anode, a protecting insulator connected to said anode shield and surrounding said anode insulator at the end portion of said metal member connected to said anode insulator, said anode being connected to said anode mounting member and forming a support for said protecting insulator, the joint between said anode and said protecting insulator being gas tight, a layer of conductive material interposed between said anode and said anode mounting member, and means to conduct vapors from said layer to the space within said container outside said shield including a channel leading between said anode insulator and said protecting insulator from the space occupied by said layer to said container space.
